(57) CLAIM

The ornamental design for an otoscope handle, as shown and described.

DESCRIPTION

FIG. 1 is a side view of an otoscope handle, showing my new design, the opposite side view being a mirror image thereto; FIG. 2 is a top view thereof, the bottom view being a mirror image thereto;

FIG. 3 is an end view thereof; and,

FIG. 4 is an end view thereof, opposite that shown in FIG. 3.

The surfaces or portions of the article not shown in the drawings or described in the specification form no part of the claimed design.
